UNITED STATES PATENT OFFICE.

MAX SOBLIK, OF DRESDEN-KLOTZSCHE, GERMANY.

PNEUMATIC TYPE-WRITER.

1,096,275.

Specification of Letters Patent. Patented May 12, 1914.

Application filed December 4, 1913. Serial No. 804,750.

To all whom it may concern:

Be it known that I, MAX SOBLIK, engineer, a subject of the German Emperor, and residing at 2 Gartenstrasse, Dresden-Klotzsche, Kingdom of Saxony, Germany, have invented certain new and useful Improvements in Pneumatic Type-Writers, of which the following is a specification.

The present invention relates to typewriters, described in the United States Patent 1075512 of application No. 749082 and has for its object improvements in the action of these machines employing a rotating type wheel whereby the regular operation and light working of the keys is insured.

According to the present invention, the keys are in communication with flexible spirals, which are prevented from deflection by rigid inclosing tubes, and which transmit the motion imparted to them by the keys to feed or type pawls through the intermediary of strengthened ends. Further, the spirals with their reinforced ends are not rigidly connected to the keys and the machine parts to be operated, but are merely adapted to transmit the thrust received by them to said machine parts, so that the heads of the keys may be arranged at or shifted to any suitable points of the keyboard.

In one convenient form of the invention a group of locking bars is arranged in the arc of a circle, and is secured by pawls which are displaced by the action of the keys so as to form a stop for a rotating member which determines the character upon the type wheel.

The invention also consists in the arrangement and operation of parts hereinafter more particularly described.

One convenient mode of carrying the invention into effect is illustrated by way of example in the accompanying drawings, in which—

Figure 1 is a vertical section, Fig. 2 a horizontal section A—B, and Fig. 3 represents, on an enlarged scale, the design and construction of the impulse transmitting mechanism.

The locking bars (a) are normally held depressed by a pawl (g) which is displaced by the operation of the keys (b). After the removal of the pawl (g), the bars (a) under the action of the springs (c) rise suddenly, independently of the speed of keys, into the path of the rotating member (d) and provide a stop for the same, thereby determining the character upon the wheel

(type wheel). The axle on which the three rotating members (d) are mounted, revolves the gear system (v) that has a ratio of gearing equal to three and by means of a shafting and two universal joints (w) revolves the type wheel (z). The keys (b) are arranged with stems on which are pivoted pawls (t). These pawls are turned by inclined noses (u), after having moved down the members (o), so that these return directly after being pressed, and leave the impulse transmitting means free. The locking bars (a) are provided with lower arms (j), which receive a downward blow after each imprint of type by the diaphragm (s) and serve the purpose of reengaging the locking bars with the pawl (g), so that the arm (a) can continue its rotation.

The impulse transmitting means is shown in section in Fig. 3. A fine spiral is inclosed in a tube (f) and the ends of the spiral are reinforced by tips or members (o) and (p) respectively engaging the key stems and pawls (g). Inasmuch as the space where the striking members (p) meet is very limited, the movable spirals in the stationary tubes (f) must have a very small diameter (one millimeter *circa*) and this necessitates a spiral method for their introduction. The tubes (f) have a diameter throughout slightly larger than the diameter of the spirals, so that the latter can move therein; the ends of the spirals are stiffened. In order to insert such spirals with stiffened ends in the bent tubes (f) collars (i) are placed on the members (o), and the ends of the tubes are provided with hollow nuts (m) and (n). The members (o) (p) have pins which extend within the spiral for a short distance. The outer member (o) is first secured to the spiral before its insertion into the tube; whereupon the spiral is inserted with its other end into the tube and passes therethrough as far as the hollow nut (n). The stop (i) then strikes against the hollow nut (n) and the inner member (p) can be secured. In this condition the hollow nut (m) can be inserted into the catches (q), situated beneath each of the keys and then secured by the screw-cap (l) and by the members (k) in the holes in the wall (r). The wall (r) is connected with the key board (x) which is fastened by screws (y) on the casting of the machine in order to take off the keyboard with the mounted spirals and tubes.

Having thus particularly described and ascertained the nature of my said invention and in what manner the same is to be performed, I declare that what I claim is:—

- 5 1. In a typewriter, a type wheel, a type wheel locking member, a key, a tube extending from the key toward the type wheel locking member, a flexible spiral spring within said tube, a reinforcing tip fitted to the outer end of the spring and adapted to be operatively engaged by the key, and means for operatively connecting the inner end of the spring to the type-wheel locking member.
- 10 2. In a typewriter, a type wheel, a type wheel locking member, a pawl engaging the same, a key, a tube extending from the key toward the type wheel locking member, a flexible spring within said tube, a reinforc-

ing tip fitted to the inner end of the spring 20 and adapted to operatively engage the pawl, and means for operatively connecting the outer end of the spring to the key.

3. In a typewriter, a type wheel, a series of spring-controlled type wheel locking bars 25 arranged in the arc of a circle, pawls adapted to engage said bars, a type wheel controlling member adapted to be engaged by the locking bars, a series of keys, a series of tubes extending from the keys toward the 30 locking bars, and a series of flexible spirals within said tubes that are adapted to transmit the movement of the keys to the pawls.

MAX SOBLI
